APPARATUS FOR MIXING VISCOUS MATERIAL WITH STOCK FEED

Robert A. Nelson, Burley, Idaho

Application December 2, 1941, Serial No. 421,391

2 Claims. (Cl. 257—241)

The present invention relates to new and useful improvements in machines for mixing molasses, syrup, and other viscous materials with grain or similar granular material to produce a stock food and the invention has for its primary object to provide means for heating the viscous material and maintaining the same in a heated condition for facilitating the mixing thereof with the grain or other stock food.

A further object is to provide a device of this character of simple and practical construction, which is efficient and reliable in performance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which:

Figure 1 is a side elevational view.

Figure 2 is a top plan view.

Figure 3 is a longitudinal sectional view through the heating cylinder.

Figure 4 is a fragmentary sectional view through the two-way valve taken substantially on a line 4—4 of Fig. 1.

Figure 5 is a sectional view taken substantially on a line 5—5 of Figure 2 and illustrating the pump, and

Figure 6 is a sectional view through the screen taken substantially on a line 6—6 of Figure 2.

Referring now to the drawings in detail wherein for the purpose of illustration I have disclosed a preferred embodiment of the invention the numeral 5 designates a storage tank having a man-hole cover 6 in its top portion to provide access to the interior of the tank.

A supply pipe for the molasses or syrup, leading from a suitable source of supply, is designated at 7 and having a control valve 8 in the pipe, the pipe leading to the intake end of a pump 9 driven by a shaft 10 by means of a pulley 11 from a suitable source of power, the shaft having a transmission mechanism 12 interposed therein of conventional construction for driving the pump at a selected speed.

A pipe 13 leads from the discharge end of the pump and extends into a substantially cylindrical heating chamber 14 where the pipe is formed into a coil 15. A branch pipe 16 leads from the feed pipe 13, the terminal of the pipe 16 with the pipe 13 having a two-way valve 17 therein to selectively control passage of the fluid either

through the pipe 13 into the coil 15, or through the branch pipe 16 which is connected to the top of the storage tank 5.

From the coil 15 the pipe extends outwardly through the heating chamber, as shown at 18, the pipe 18 having branches 19 and 20, the branch 19 having a control valve 21 therein and communicates with the top of the storage tank 5 while the branch 20 communicates with a spray nozzle 22 extending through the top of a cylindrical conveyor 23, the branch 20 also having a control valve 24 therein.

Interposed in the pipe 18 is a meter 25, a pressure and temperature indicator 26 and a volume control valve 27, the meter, temperature and pressure indicator and the volume control valve being of conventional construction.

The heating chamber 14 is closed at each end and provided with a longitudinally extending partition 28 forming separate compartments 29 and 30, the coil 15 being positioned in the compartment 29. A pipe 31 connects with one end of the chamber 14 and is adapted for connection with the exhaust pipe of an internal combustion engine for feeding exhaust gases to the heating chamber. Pivoted to one end of the partition 28, adjacent the intake end, is a damper valve 32 adapted for swinging into a position for admitting the exhaust gases either into the chamber 29 or into the chamber 30, the damper valve having a control lever 33 positioned outwardly of the heating chamber. Extending from the rear end of the heating chamber 14 is a pipe 34 constituting a discharge pipe for the chamber 29, the pipe 34 leading into the storage tank 5 and communicating with a heating chamber 35 positioned in the bottom portion of the storage tank. The pipe 34 connects to one end of the heating chamber 35 and at the opposite end thereof is connected a return pipe 36 leading back to the chamber 30 of the heating chamber 14. The chamber 30 of the heating chamber 14 is provided with an exhaust stack 37 extending through the top of the heating chamber.

One end of the conveyor 23 is provided with a feed hopper 38 into which the grain or other granular feed is adapted to be admitted into the conveyor, the conveyor having a feed screw 39 mounted therein on a shaft 40 having a pulley 41 at one end adapted to be driven by a belt 42 from a suitable source of power. At the discharge end of the conveyor is provided a trough 43.

The supply pipe 7 is also provided with a branch pipe 44 communicating with the bottom portion

of the storage tank 5 and having a screen 45 positioned therein as well as a cut-off valve 46.

The system thus provided will permit molasses or other liquid material to be fed directly to the mixer 23 from the main supply pipe 7 after passing through the heater 14, by closing valves 21 and 46 and opening valves 8 and 24, and operating valve 17 to opening the line leading to the coil 15 and closing the line 16, or the molasses may be fed to the mixer from the tank 5 by closing valve 8 and opening valve 46 without disturbing the remaining valves.

Likewise the molasses may by-pass the heater and enter the tank 5 directly from the pump by manipulating the two-way valve 17 to close the coil 15 and open the line 16, and the molasses may also be fed to the tank after passing through the heater and cut off from the mixer by opening valve 21 and closing valve 24.

By operating the valves as indicated the supply to the mixer may be cut off or on without interrupting the operation of the pump.

It is believed the details of construction and manner of use of the device will be readily understood from the foregoing without further detailed explanation.

Having described the invention what is claimed is:

1. A heating system for heating liquid for a mixing apparatus and comprising a liquid feed pipe leading from a source of supply to the mixing apparatus, an outer heating chamber surrounding a portion of the feed pipe, a hot air supply pipe connected to the outer chamber, a storage tank, an inner heating chamber in the storage tank, an exhaust pipe leading from the outer chamber to the inner chamber, branch pipes leading from the liquid feed pipe to the storage tank in advance of the outer heating chamber and beyond the heating chamber, and valves for said pipes.

2. A heating system for liquids comprising a tank, a heating chamber outwardly of the tank and having a plurality of compartments therein, means for selectively heating the compartments of the chamber, a heating chamber in the tank, a discharge pipe leading from one compartment of the outer chamber to the inner chamber, a return pipe from the inner chamber leading to the other compartment of the outer chamber, a liquid supply pipe extending through said one compartment and also connected to the tank, and a valve in the pipe controlling passage of liquid to said compartment and to said tank.

ROBERT A. NELSON.
